UNITED STATES PATENT OFFICE

2,561,383

COSMETIC PROSTHETIC HAND

Edward T. Larkins, Daytona Beach, Fla., Bernard S. Thomas, Washington, D. C., and David R. Fetter, Hyattsville, Md.

Application October 21, 1947, Serial No. 781,110

12 Claims. (Cl. 3—12)

(Granted under the act of March 3, 1883, as amended April 30, 1928; 370 O. G. 757)

1

The present invention relates generally to prosthetic devices and more particularly to a self-closing prosthetic hand mechanism which simulates the gripping action of the human hand, and is adapted to be covered by a cosmetic plastic glove which closely simulates the color, texture, configuration, and appearance of the human hand.

A difficulty encountered in prosthetic hands of this character heretofore devised has been in combining high utility value with natural appearance. A further difficulty has been in providing a mechanism which is easy to operate and which has a grip of sufficient strength for normal use.

In the device of the present invention these difficulties have been substantially obviated in that the mechanism is constructed and arranged to follow closely the skeletal formation and finger movement of the human hand, and, therefore, is particularly adapted for use with the aforementioned cosmetic plastic glove. The mechanism is also especially adapted for use with a shoulder-operated cable mechanism in that the hand mechanism is normally spring-urged to the closed position, thereby obviating a tedious and continuous pull on the cable while holding objects with the hand. The finger structure of the mechanism is mechanically arranged to provide anti-friction devices at certain of the joints thereof whereby the fingers are moved to an open position by a small pull on the cable, a quality particularly desirable where it is necessary to grasp and release objects frequently.

An object of the present invention is to provide a new and improved prosthetic hand mechanism for use with a cosmetic plastic glove.

Another object is to provide a prosthetic hand mechanism which closely simulates the skeletal formation and movement of the human hand.

Still another object is to provide a prosthetic hand mechanism which is operated by a small pulling force.

A further object is to provide a prosthetic hand mechanism in which the finger structure is normally spring-closed.

A still further object is to provide a spring-closed prosthetic hand mechanism in which the finger structure is operated throughout the movement thereof by a more nearly uniform pulling force.

A still further object is to provide a prosthetic hand mechanism which is light in weight, simple in design, and durable in operation.

Still further objects, advantages, and improve-

ments will become apparent from the following detailed description taken in connection with the accompanying drawings in which:

Fig. 1 is a plan view of the device of the present invention according to a preferred embodiment thereof and showing the mechanism in dotted lines;

Fig. 2 is a sectional view taken along line 2—2 of Fig. 1;

Fig. 3 is a view substantially as shown in Fig. 2 and showing the device in the open position;

Fig. 4 is a plan view of the mechanism, the cover or glove being removed;

Fig. 5 is a side elevational view of the mechanism, the cover or glove being removed;

Fig. 6 is a sectional view taken along line 6—6 of Fig. 5;

Fig. 7 is a sectional view taken along line 7—7 of Fig. 4; and

Fig. 8 is a sectional view taken along line 8—8 of Fig. 5.

Referring now to the drawings in which like numerals of reference are employed to indicate like parts throughout the several views, there is provided a mechanism generally indicated 15 and including a supporting disk 16, perforated as at 11 to decrease the weight thereof and having a threaded hollow attaching shank 12 adapted to receive a nut 13. The shank 12 and nut 13 serve to secure the disk 16 to a conventional arm boot 14 which may be fastened to the arm stump of the wearer in any well known manner.

The mechanism 15 also includes a frame member 16 attached to the disk 16 by means of a screw 17. A locking pin 18 extends through disk 16 and into frame member 16, thereby to prevent rotation of the frame member with respect to the disk.

The frame member 16 is formed with a reduced portion 19 to receive a cam pulley 21. A pivot pin 22 is press-fitted into a bore 23 of portion 19. Pin 22 receives anti-friction bearing 24 of cam pulley 21 which is held against displacement by a screw 25 positioned in one end of the pin 22. Cam pulley 21 has secured thereto an eccentrically mounted pin 26, the purpose of which will be hereinafter more fully described.

The body member 16 is formed at one end with an angular extension 27 having a cut-out portion 28 adapted to receive a bearing cap 29 secured thereto by screws 31 and 32. Extension 27 has a bifurcated end adapted to rotatably receive a transversely disposed rod 33. Fixedly mounted on rod 33 and a similar rod 34 are four arched finger bars 35, 36, 37, and 38 which

are shaped to follow the skeletal formation of the human fingers. This construction insures unitary action of the four finger bars about the axis of rod 33. Finger bar 36 has an opening 39 formed therein to accommodate a pin 41. A bifurcated link 42 is pivoted on pin 41 and has one end of a connecting bar 43 pivotally attached thereto as at 44. The other end of connecting bar 43 is pivotally joined to cam pulley 21 by the aforementioned pin 26.

Fastened as at 40 to the pulley 21 is a cable 45 which passes around a portion of the periphery of the pulley, through an opening 50 in the disk 10 and continues up the arm of the wearer to the usual shoulder operating mechanism (not shown). It will be apparent that when cable 45 is pulled, pulley 21 is rotated, thereby causing movement of the finger bars to an open or non-gripping position as the pull on the cable is transmitted through pin 26, connecting bar 43, and link 42. It further will be apparent that any desired opening of the finger bars may be made by governing the amount of pull on the cable 45.

The cam pulley is so shaped as to provide an effective torque arm which increases, Fig. 4, as the pulley is rotated and the tension of the finger actuating springs is increased whereby the finger structure is adapted to be operated throughout the movement thereof by a more nearly uniform pull on the cable.

It will be seen in Fig. 4 of the drawings that when the finger structure is in the closed position, the pivotal axes of the pulley, bar, and link are in substantial alignment, thereby providing a substantially irreversible lock, that is, the finger structure can be moved by a pull on cable 45 and cannot readily be moved by a pull on the fingers themselves, thus there is little likelihood of the finger structure inadvertently releasing small articles held thereby.

In order to bring the finger bars to the closed or gripping position and also to provide a strong grip for the finger bars there are provided a pair of springs 46 mounted on a shaft 47 which is rotatably mounted in complementary halves of a bore 48 in angular extension 27 and bearing cap 29. The shaft 47 has formed therein a pair of transverse slots 49 adapted to receive one end of each of the springs 46 respectively. The springs are secured to shaft 47 by transverse pins 60. An important feature of the device is the reduction of friction by providing anti-friction rollers 51 between the points of contact of springs 46 and rod 34.

By urging the free ends of springs 46 against rollers 51, a lever arm corresponding approximately to the distance between rods 47 and 34 is provided for increasing the torque on rod 33, as the finger structure is moved away from the thumb bar, over and above that which would be applied thereto if the springs were mounted on shaft 33 with the same tension in the closed position, for the reason that, by interposing pivotal shaft 33 between shafts 34 and 47, the lever arm of each of springs 46 decreases as the finger structure is opened, whereby the force applied to the finger structure by the springs further increases as the finger structure is progressively opened. The foregoing arrangement has the advantage that the gripping force between the thumb bar and the finger structure increases as larger and heavier objects are grasped therebetween.

Mounted at one end of the shaft 47 is a toothed ratchet wheel 52 which is engaged by a pawl

53 mounted on shaft 54 rotatably held in complementary halves of the bore 55 in extension 27 and cap 29. The end of shaft 47 is formed as at 56 to receive a key (not shown) for the purpose of adjusting the tension on springs 46.

Secured to the body member 16 and at one side thereof by screws 57 and 58 is a thumb bar 59 which is bent to follow generally the skeletal formation of the human thumb the tip thereof coming to a point substantially midway of the tips of finger bars 35 and 36 and extending slightly therebeyond. As will be seen in Fig. 8, the screw 58 may be used to adjust the thumb bar 59 to the position desired. A purpose of the above arrangement is to provide a convenient means of preadjusting the position of thumb bar 59 so as to facilitate the gripping of small objects such as pencils, pens, etc. The thumb bar may be rigidly attached to the frame, in which case angular adjustment of the bar may be effected by heating and bending.

A guard plate 72 is secured to the angular extension 21 by screw 31 to prevent the ratchet mechanism and springs from becoming entangled in a glove or cover 61 to be hereinafter more fully described.

In order to provide a prosthetic hand having a natural appearance the cover or glove 61 is used with the device of the present invention. The glove 61 is composed of a flexible plastic material which closely simulates the color, texture, and appearance of the human skin. It is formed by a molding process, the molds being produced by a process in which a human hand is used to provide the form and detail thereof. A glove is therefore provided which has substantially all the intricate details of the human hand as well as the esthetic character thereof.

The glove 61 has a palm portion 62 which covers the major part of the mechanism 15, a thumb portion 63 which covers the thumb bar 59 and finger portions 64, 65, 66, and 67 which cover the finger bars 35, 36, 37 and 38 respectively. Wrist portion 68 is formed with a slit 69 to facilitate the application or removal of the glove. A slide fastener 71 is provided to close the slit 69.

The glove 61 is formed of a flexible semi-elastic plastic material, in order to provide a covering for the mechanism which appeals to the esthetic senses, and, also, accommodates the movement of the mechanism without undue distortion of the glove. In order to prevent excessive wear of the glove 61 in service and to cooperate with the glove in providing an improved gripping medium, resilient fillers 75 formed of a suitable material such, for example, as foam plastic are mounted on the finger bars and the thumb bar and are disposed respectively within the fingers and thumb of the glove.

It is also a feature of the invention that the cam pulley 21 has formed on the periphery thereof a radial shoulder 73 for contact with the shoulder 14 on frame 16 in order to provide a stop to prevent excessive opening of the mechanism. It is, of course, understood that while the device of the present invention has been shown as being arranged for attachment to the right arm, the mechanism and glove may be made in reverse order for use with the left arm.

From the foregoing, it should now be appreciated that a prosthetic hand mechanism has been provided in which the thumb and finger structure may be formed of a light and strong material such, for example, as magnesium where-

by these parts may be provided with sufficient strength to retain their initial hand simulating characteristics notwithstanding a wide diversity of use and to avoid permanent strains and distortion resulting from accidental bending of the parts in service, while at the same time providing a skeletal hand structure of light weight and precise mechanical movement.

Whereas a preferred embodiment of the invention has been disclosed in particularity herein which gives satisfactory results, it will be apparent that additional embodiments and modifications thereof may occur to those skilled in the art without departing from the spirit and scope as defined by the appended claims.

The invention herein described and claimed may be manufactured and used by or for the Government of the United States of America for governmental purposes without payment of any royalties thereon or therefor.

What is claimed as new and desired to be secured by Letters Patent of the United States is:

1. A mechanism for a prosthetic hand, comprising the combination of a frame member, a thumb bar attached to said frame member, a finger structure mounted for pivotal movement on said frame member, yieldable means for urging said finger structure toward said thumb bar, said yieldable means increasing in tension as the finger structure is moved away from the thumb bar, link members attached together and to said finger structure, a cam pulley mounted for rotation on said frame, and a cable passed around the pulley and secured thereto for coaction therewith, said pulley having an eccentric pin for operative connection with the terminal one of said link members and being cam shaped in such a manner as to increase the leverage of the cable thereon as the tension of said yieldable means increases during the movement of the finger structure away from the thumb bar thereby to provide a more nearly uniform tension on the cable throughout said movement of the finger structure.

2. A prosthetic hand mechanism, comprising the combination of a frame, a thumb bar fixedly attached to said frame, a finger structure mounted for pivotal movement on said frame, spring means for yieldably urging said finger structure toward said thumb bar, said spring means increasing in tension as the finger structure is moved away from the thumb bar, a cable operated cam-shaped pulley rotatably supported on said frame and link means interconnecting the pulley and the finger structure for moving the finger structure away from the thumb bar as the pulley is rotated by a pull on the cable whereby the leverage of the cable thereon is increased during movement of the finger structure away from said thumb bar and a simulation of the movement of the human fingers is provided by a more nearly uniform tension in the cable.

3. A prosthetic hand mechanism, comprising, in combination, a frame adapted to be secured to an arm boot and having an angular extension thereon, a thumb bar mounted on said frame, a unitary finger structure comprising four fingers rigidly interconnected and mounted for unitary pivotal movement on said extension, a pair of springs, means including a settable shaft mounted on said extension for supporting the springs in a position corresponding to a predetermined setting of said shaft thereby to urge said finger structure toward said thumb bar, a ratchet and pawl secured to said shaft and extension respectively for maintaining said shaft

in a set position thereby to vary the initial tension on said pair of springs, and means including a cable operated pulley having a peripheral cam surface thereon in engagement with the cable for moving the finger structure away from the thumb bar and concurrently therewith increasing the leverage of the cable with respect to the pulley in response to tension applied to the cable.

- 10 4. A prosthetic hand mechanism adapted to be covered by a cosmetic plastic glove, comprising, in combination, a frame member having an angular extension, a thumb bar attached to said frame member and disposed within the thumb of the glove, a unitary finger structure pivotally mounted on said angular extension and adapted to be moved from a closed position to an open position with relation to said thumb bar, the fingers of said finger structure being disposed within the fingers of the glove, spring means for normally maintaining the finger structure in the closed position, said spring means increasing in tension as the finger structure is moved to said open position, means supported on said frame member and including a cable operated cam-shaped pulley and a link connection between the pulley and the finger structure for moving the finger structure to the open position as the pulley is rotated by a pull on the cable, said pulley having a cam-shaped periphery for increasing the effective leverage of the cable thereon as the tension in said spring means increases thereby to provide a more nearly uniform pull on the cable and simulation of movement of the human hand.
- 15 5. In a prosthetic hand mechanism adapted to be covered by a cosmetic plastic glove, the combination of a frame member having an angular extension thereon, a thumb bar attached to said frame member, a finger structure mounted for pivotal movement on said angular extension and adapted to be moved with relation to said thumb bar, spring means for normally maintaining said finger structure adjacent the thumb bar, ratchet means operatively connected to said spring means for varying the tension of said spring means, a cable, and means including a pulley for coaction with said cable and a link connection between the pulley and the finger structure for providing an irreversible lock for the finger structure when in adjacency with the thumb bar and for moving the finger structure away from the thumb bar against the opposing force of said spring means when a sufficient pulling force is exerted on the cable.
- 20 6. A mechanism for a cosmetic prosthetic hand, comprising the combination of a frame member adapted to be secured to a boot member and having an angular extension, a thumb bar attached to said frame member, a finger structure pivotally mounted on said angular extension and adapted to be moved with relation to said thumb bar, means including a plurality of springs for yieldably urging said finger structure into adjacency with the thumb bar, said springs increasing in tension during movement of the finger structure away from the thumb bar, means including a cam-shaped pulley rotatably supported on the frame, a cable secured to the pulley and passed over a peripheral portion thereof for coaction therewith and a link connection between the pulley and the finger structure for moving the finger structure with relation to the thumb bar and in opposition to the tension of said springs when the cable is pulled, said peripheral portion of the pulley being cam shaped to increase
- 25 70 75

the effective leverage of the cable on the pulley as the tension in said springs increases in response to said movement of the finger structure, and means including a ratchet and pawl mechanism operatively connected to said plurality of springs and adjustable at will for varying the tension of the springs in accordance with the degree of gripping force desired between the finger structure and the thumb bar.

7. A prosthetic hand mechanism for use with a glove simulating the color, texture, and contour of the human hand, comprising the combination of a frame member, a thumb bar mounted on said frame member and disposed within the thumb of the glove, a finger mechanism mounted for pivotal movement on said frame member and having fingers respectively disposed within the fingers of the glove, means including an adjusting screw for moving the thumb bar laterally with relation to a pair of said fingers of the finger mechanism, spring means for yieldably and normally maintaining said finger mechanism adjacent said thumb bar, said spring means increasing in tension during movement of the finger mechanism away from the thumb bar, and means including a cable and a cam-shaped coacting pulley having said cable wrapped thereon for moving the finger mechanism away from the thumb bar, said pulley being cam shaped to provide an increasing lever action of the cable on the pulley as the tension of the spring means increases thereby to operate the finger mechanism throughout said movement thereof in response to a more nearly uniform tension applied to the cable.

8. In a cosmetic prosthetic hand, the combination with a resilient plastic glove of a mechanized skeletal thumb and finger structure disposed therewithin and comprising a frame member having an angular extension, finger bars simulating the skeletal formation of human fingers, a pair of transverse parallel rods for rigidly securing said finger bars in spaced relation simulating the fingers of a partially closed human hand, one of said pair of rods being journaled in said angular extension transversely thereof thereby to pivotally support the finger bars as a unit thereon, a thumb bar simulating the human thumb and adjustably secured to said frame member for lateral bending movement with respect to said finger bars, the other of said pair of rods having a plurality of anti-friction rollers carried thereon, a shaft journaled in the angular extension transversely thereof and parallel to said pair of rods, a plurality of coil springs secured to said shaft and having arms extending into engagement respectively with said plurality of rollers so as to yieldably urge the finger bars into gripping relation with respect to said thumb bar and to progressively increase the tension in the springs as the finger bars are progressively moved to open position with respect to the thumb bar, a ratchet wheel carried by the shaft and a cooperating pawl carried by the angular extension for adjusting the tension in said springs upon rotation of the shaft, a cable, a cam-shaped pulley rotatably supported on the angular extension and secured to said cable and having the cable wrapped thereon for coaction therewith, said pulley being cam shaped in a manner to increase the leverage of the cable on the pulley as the pulley is rotated upon pulling the cable, a crank pin secured to the pulley, a first link pivotally secured to one of said finger bars, and a second link pivotally interconnecting said crank pin and said first link, said pulley and said first

and second links being constructed and arranged to resist opening of the finger bars from the closed position thereof by a force applied thereto.

9. A prosthetic hand mechanism comprising, a support, coacting thumb and finger structures respectively secured to and pivotally mounted on said support, a shaft journaled in the support parallel to the pivotal axis of the finger structure, a plurality of anti-friction rollers carried by the finger structure, said pivotal axis being disposed intermediate said shaft and said rollers, a plurality of coil springs carried by the shaft and having arms respectively extending into engagement with said rollers so as to yieldably urge the finger structure into gripping relation with respect to the thumb bar and to progressively increase the tension in the springs as the finger structure is opened progressively with respect to the thumb bar, a cable, a cam-shaped pulley rotatably mounted on said support and secured to the cable and having the cable wrapped thereon for cooperation therewith, said pulley being cam shaped in a manner to increase the leverage of the cable on the pulley upon rotation thereof as the cable is pulled, and a linkage interconnecting the pulley and the finger structure for pivotally moving the finger structure as the pulley is rotated.

10. In a cosmetic prosthetic hand, the combination of a resilient plastic glove and a mechanized skeletal thumb and finger structure disposed therewithin and comprising a frame having an angular extension, finger bars simulating the skeletal formation of human fingers mounted for pivotal movement on said angular extension and respectively disposed within the fingers of the glove, a thumb bar simulating the skeletal formation of a human thumb fixedly mounted on said frame and disposed within the thumb of the glove, resilient fillers mounted on the finger bars and the thumb bar and respectively disposed within the fingers and thumb of the glove, spring means for yieldably maintaining the finger bars adjacent the thumb bar, said spring means increasing in tension during movement of the finger bars away from the thumb bar, and means including a cable and a coacting cam-shaped pulley secured to said cable and having the cable wrapped thereon for moving the finger bars away from the thumb bar in response to a pull on the cable, said pulley being cam shaped to increase the leverage of the cable on the pulley thereby to compensate for said increase in tension of the spring means during said movement of the finger bars.

11. A mechanism for a prosthetic hand comprising, in combination, a frame member adapted to be secured to the stump of a human arm, said frame member having an angular terminal extension, a thumb bar adjustably mounted on said frame member, a unitary finger structure having a plurality of fingers thereon and mounted on said angular terminal extension for pivotal movement with respect to said thumb bar, a bar extending through said plurality of fingers adjacent said pivotal mounting and having a pair of anti-friction rollers thereon, a shaft rotatably mounted in and extending beyond the sides of said frame member in spaced adjacency to said pivotal mounting, a pair of helical springs fixedly mounted on said shaft respectively adjacent the sides of said frame member and having extended ends thereof engaging said rollers, a ratchet wheel secured to said shaft, a pawl mounted on said frame and engaging the ratchet wheel whereby the initial tension on said springs is adjustably

maintained, said springs yieldably urging said finger structure toward a gripping position with respect to the thumb bar and increasing in tension as the finger structure moves to open position, a peripherally grooved cam-shaped pulley, anti-friction means for pivotally mounting the pulley on said frame, a pin eccentrically mounted on the pulley, a link interconnecting said pin and said finger structure at a point slightly beyond said bar and for moving the fingers to said open position as the pulley is rotated, means including a cable for rotating said pulley, said cable having one end fastened to the pulley and normally riding in said peripheral groove, said cam-shaped pulley being shaped to increase the lever arm thereof as the tension of said springs increases during movement of the fingers to said open position thereby to provide a more nearly uniform pulling force on the cable during movement of the finger structure to said open position.

12. A prosthetic hand mechanism comprising, in combination, a frame, a thumb bar attached to the frame, a unitary finger structure pivotally supported on said frame for pivotal movement toward and away from said thumb bar, spring means for yieldably urging said finger structure toward the thumb bar, said spring means increasing in tension as the finger structure is moved away from the thumb bar, a cam pulley rotatably supported on said frame, a cable se-

cured to the pulley and passed around a peripheral portion thereof, and link means interconnecting said finger structure and said cam pulley for moving the finger structure away from the thumb bar as the pulley is rotated by a pull on the cable, said peripheral portion being shaped to increase the leverage of the cable on the pulley to compensate for said increase in tension of said spring means as the pulley is rotated by the cable whereby the pull on the cable is rendered more nearly uniform during said movement of the finger structure away from the thumb bar.
